CONTROL FOR REFRIGERATING APPARATUS

Roger W. Hastings, Springfield, Mass., assignor to Westinghouse Electric & Manufacturing Company, East Pittsburgh, Pa., a corporation of Pennsylvania

Continuation of application Serial No. 139,873, April 30, 1937. This application September 13, 1939, Serial No. 294,613

11 Claims. (Cl. 200—138)

5 My invention relates to control apparatus for refrigerating machines and it has for an object to provide improved apparatus of this kind. This application is a continuation of my application Serial No. 139,873 originally filed April 30, 1937.

10 A further object of the invention is to provide a compact control mechanism that is inexpensive to construct and which may be readily applied to various forms of refrigerating machines.

15 It is a further object of the invention to provide an improved refrigerator control employing a snap-acting thermal device that may be readily adjusted to maintain different refrigerating temperatures.

20 20 A still further object of the invention is to provide an improved control mechanism for a refrigerating element including a hermetically-sealed switch structure which may be readily adjusted to a plurality of positions wherein the element is maintained at different temperatures and including a position wherein the element is rendered inactive for cooling.

25 25 These and other objects are effected by my invention as will be apparent from the following description and claims taken in connection with the accompanying drawing, forming a part of this application, in which:

30 30 Fig. 1 is a diagrammatic view of a domestic refrigerator having my improved control mechanism applied thereto;

Fig. 2 is a sectional view in a vertical plane through the control mechanism shown in Fig. 1 and viewed from the same point as Fig. 1; and,

35 35 Figs. 3, 4 and 5 are sectional views taken along the lines III—III, IV—IV and V—V of Fig. 2, respectively.

40 40 Reference will now be had to the drawing for a description of the invention. In Fig. 1, I have shown a conventional domestic refrigerator cabinet 10 having a compartment 11 formed therein for food to be refrigerated. An evaporator 12 is disposed for cooling the air in the compartment 11 and may be provided with shelves 13 for supporting trays 14 in which fluid to be congealed is contained. Refrigerant is circulated through the evaporator 12 by a refrigerant condensing unit shown generally at 15 and including a compressor 16, driven by an electric motor 17, and a condenser 18. The latter is cooled by a fan 19 that is preferably motor-driven as shown. Vaporous refrigerant is conveyed from the evaporator 12 through a suction conduit 21 and the compressed gas is conveyed to the condenser 18 through a conduit 22. Liquefied refrigerant passes through a conduit 23 to the evaporator 12

and is controlled by any suitable expansion device, such as, for example, a conventional high side float valve 24.

5 The compressor motor 17 receives electrical energy from a suitable source shown as line conductors L₁ and L₂. Conductors 25 and 26 connect the motor 17 to the conductors L₁ and L₂ as shown; the conductor 26 having my improved control device 27 connected therein. The device 27, as described hereinafter, includes provisions 10 for starting and stopping operation of the compressor 16 and motor 17 in response to predetermined high and low temperatures of the evaporator 12. The apparatus described heretofore operates on the well-known compressor-condenser-expander cycle and it is deemed unnecessary to describe in detail the operation thereof.

Reference will now be had to Figs. 2 to 5, inclusive, for a detailed description of the device 27 shown in Fig. 1. The latter includes a cylindrical casing 28 having mounting ears 29 that are strapped or otherwise suitably secured to the evaporator 12, a portion of which is shown in Figs. 2 and 4. The casing 28 includes an end wall 30 and is closed at its other end by a wall 20 25 31 having a flexible portion shown, by way of example, as an expandable bellows 32. The latter is soldered or otherwise suitably affixed to the wall 31 to provide a gas-tight connection at 31a. The wall 31 is soldered or otherwise connected to 30 the casing 28 to provide a gas-tight connection at 31b. The casing 28 and the flexible wall 31 define a hermetically-sealed chamber 33 for housing a switch 34 and a thermal responsive disc 46, to be referred to more in detail herein- 35 after. The soldered connection at 31b is spaced from the disc 46 so that the latter will not be affected by heat when the wall 31 is affixed to the casing 28. This is a desirable feature of my control construction as thermal elements of the 40 type shown may have their temperature characteristics seriously affected if subjected to a high temperature.

45 The switch 34 includes a stationary and a movable contact 35 and 36, respectively, for controlling energization of the motor 17. Support for the stationary contact may be provided by a rigid conductor 37 that extends through a pair of gas-tight insulating seals 38 in the wall 31. One portion of the conductor 26 is connected to the conductor 37 as shown at 39. The movable contact 36 is carried by a spring 41 that biases the contact 36 toward the contact 35 and which may include laterally-extending portions 42 secured to a conducting strip 43, the latter extending 50 55

through gas-tight insulating seals 44 in the wall 31. The other portion of the conductor 26 is connected to the strip 43 as shown at 45. I have shown four seals passing through the wall 31 so that a convenient support for the contacts 36 and 35 may be obtained and for increasing the current-carrying capacity of the seals, but it will be understood that two insulating seals may be employed if desired for conducting the current to the contacts of the switch.

The switch structure 34 is actuated by the thermal responsive element or disk 46, substantially circular in shape and of bi-metal construction. This type of element is well known in the art and operates in a snap-acting manner when subjected to predetermined temperatures. As shown in Fig. 4, the disk 46 is in its "switch closing" position. When the temperature of the disk 46 is depressed to a predetermined value, it snaps to the position shown in broken lines and thereby moves the switch 34 to its open position. The disk 46 is disposed within the portion of the chamber 33 adjacent the evaporator 12 so that it quickly reflects changes in temperature of the evaporator 12. The disk 46 may be clamped in place at its periphery by a plate 47 and crimps 48 in the casing 28, as shown.

The disk 46 carries a socketed fitting 49 that is slidably supported by the plate 47. An insulating switch actuating yoke 51 is maintained in engagement with the socketed fitting 49 by a spring 52, the latter bearing against the inside of the flexible bellows 32. An opening 53 is provided in the yoke 51 through which the contact carrying spring 41 extends. As the disk 46 snaps to the position shown in broken lines, the side wall of the opening 53 engages the spring 41 and moves it sufficiently to disengage the contact 36 from the contact 35. The lost motion provided by the spring 41 and opening 53 assures good contact between the contacts 35 and 36 when closed.

As shown in Fig. 2, a pinch tube 54 may be secured in the wall 31 so that the chamber 33 may be filled with an inert gas during assembly 46 whereby oxidation of the contacts is reduced and the capacity of the switch increased.

In order to vary the temperatures to which the disk 46 responds to open and close the contacts, I provide an operator's adjustment as shown generally at 55. This adjustment includes a cam 56 carried by a shaft 57 that is journaled in a cap 58, the latter being fixed to the casing 28 as described hereinafter. An adjusting handle or knob 59 is secured to the shaft 57 and is readily accessible to the operator as is apparent from Fig. 1. Temperature readings or other indicia may be indicated on a plate 61 carried by the casing 28 and readable in conjunction with a pointer on the knob 59.

The cam 56 engages a seat 62 that bears against the bellows 32, the seat 62 having slots 63 formed therein through which the shaft 57 projects. The seat 62 includes a projection 64 that registers with depressed portions 65 to 69, inclusive, formed in the cam in the various positions of the latter. When the depression 65 is in registry with the projection 64, the bias of the spring 52 is at a minimum, and, accordingly, the temperature of the evaporator 12 to which the disk 46 responds to close the switch 34 is relatively low. Therefore, in this position of the cam 56, the switch is operated to maintain the evaporator 12 at its lowest value. Rotating the cam counter-clockwise as viewed in Fig. 2 increases the bias of the spring 52 and increases

the temperatures of the evaporator to which the disk 46 responds to close and open the switch 64. The evaporator 12 is maintained at its maximum operating temperature when the projection 64 is disposed in the depression 68 on the cam. 5

A position of the cam is provided in which the switch 34 is maintained open at which time the condensing unit 15 is rendered inactive. In this inactive or "off" position, the depression 69 in the maximum raised portion of the cam engages the projection 64. In this position, the end of the bellows 32 engages the adjacent end of the yoke 51 and moves the yoke to the left a sufficient distance to maintain the switch 34 open, regardless of the temperature of the disk 46. 10

The cap 58 is made adjustable with respect to the casing 28 in order that a preliminary, or factory adjustment may be given to the spring 52, independently of the operator's adjustment 55. This adjustment is desirable for determining the temperature to which the control responds in the different positions of the operator's adjusting mechanism 55. As shown, I provide a connection between the cap 58 and the casing 28 which permits axial movement of one of these elements 25 with respect to the other. The casing may be provided with a slot 71 through which a binding screw 72 extends, the screw 72 being threaded in the cap 58. Accordingly, the cap 58 may be moved inwardly or outwardly with respect to the 30 casing 28, whereby more or less bias is imparted to the spring 52. When the proper bias is obtained, the screw 72 is tightened for binding the cap 58 to the casing 28.

As shown in Figs. 2 and 3, the conductor 26 35 extends through a bushing 73 in the cap 58. The latter may be slotted as shown at 74 for the reception of the bushing 73 whereby the connection of the conductor portions 26 to the loop 38 and strip 43 may be readily made and the cap 58 40 slide over the bushing 73 during its assembly to the casing 28.

From the foregoing, it will be apparent that I have provided an improved control mechanism having a sealed-in switch mechanism, which control mechanism may be readily assembled to a refrigerant evaporator. The heat responsive disk and sealing bellows are aligned for the sake of compactness and the adjusting shaft 57 of the operator's adjustment 55 is arranged at right 50 angles to the axis of the bellows and disk so that the adjusting handle 59 may be disposed at the front of the evaporator where it is accessible. Furthermore, I have provided, in a control of this type, an adjusting mechanism movable to a plurality of selective positions in which various evaporator temperatures are maintained and including a position wherein the condensing unit 55 is inactive for cooling.

While I have shown my invention in but one 60 form, it will be obvious to those skilled in the art that it is not so limited, but is susceptible of various changes and modifications without departing from the spirit thereof, and I desire, therefore, that only such limitations shall be 65 placed thereupon as are imposed by the prior art or as are specifically set forth in the appended claims.

What I claim is:

1. In a control mechanism, the combination of 70 a casing structure having a flexible wall and defining a hermetically-sealed chamber, a switch disposed within the chamber, a thermal-responsive element subjected to temperature for actuating the switch, a spring providing a bias upon

the thermal-responsive element and the flexible wall and determining the temperatures at which said element operates, and means for adjusting the bias of the spring and movable to a plurality of positions wherein the thermal-responsive element actuates the switch at different temperatures, said adjusting means including a rotatable device, the axis of which is disposed at an angle to the direction of movement of said thermal-responsive element.

2. In a control mechanism for a refrigerating machine, the combination of a casing structure having a flexible wall and defining a hermetically-sealed chamber, a switch disposed within the chamber for controlling the operation of the refrigerating machine, a thermal-responsive element subjected to the temperature produced by the refrigerating machine for actuating the switch, a member connecting the thermal-responsive element and the switch for imparting movement of the former to the latter, a spring biasing the thermal-responsive element to one of its positions and engaging said flexible wall, and adjustable means disposed exteriorly of the casing in engagement with the flexible wall, and being movable to a plurality of selective positions for varying the bias of the spring and the temperatures at which the thermal-responsive element operates the switch, said adjustable means being adjustable to a position wherein it effects engagement of the flexible wall and said connecting member whereby the former moves the latter sufficiently to effect opening of the switch independently of the thermal-responsive element.

3. In a control mechanism, the combination of a casing structure having a flexible wall and defining a hermetically-sealed chamber, a switch disposed within the chamber, a thermal-responsive element subjected to temperature for actuating the switch, a spring engaging the flexible wall and biasing the thermal-responsive element toward its switch open position, and adjustable means engaging the flexible wall for varying the bias of the spring whereby the temperatures at which the thermal-responsive element operates the switch are varied, said adjustable means being movable to a position wherein the flexible wall engages the thermal-responsive element and forces it to a position wherein the switch is maintained open regardless of the temperature of the thermal-responsive element.

4. In a control mechanism for electrically-controlled apparatus, the combination of a casing, means for securing the casing to the apparatus, a thermal-responsive element carried by the casing in heat transfer relation with the apparatus, a switch hermetically sealed within the casing and actuated to open and closed positions by the thermal-responsive element, a spring biasing the thermal-responsive element to one of said positions, a cam rotatable to a plurality of selective positions for varying the bias of said spring, a bellows for sealing said casing and interposed between the switch and the cam, means for rotatably supporting the cam, means for adjusting the cam supporting means relative to the spring, and a readily accessible device for rotating the cam, whereby the bias of the spring and the temperatures at which the thermal-responsive device actuates the switch are varied at will.

5. In a control mechanism for electrically-controlled apparatus, the combination of a casing, means for securing the casing to the apparatus, a thermal-responsive element carried by the casing in heat transfer relation with the apparatus,

a switch hermetically sealed within the casing and actuated to open and closed positions by the thermal-responsive element, a spring biasing the thermal-responsive element to one of said positions, adjustable means for varying the bias of the spring and including a rotatable member, the axis of which is disposed at an angle to the axis of the thermal-responsive device, a bellows sealing said casing and interposed between said switch and the adjustable means and a readily accessible handle for actuating the adjustable means so that the bias of the spring and the temperatures at which the switch member is actuated to open and closed positions may be varied at will.

6. In a control mechanism for electrically-controlled apparatus, the combination of a casing structure having a flexible wall and defining a hermetically-sealed chamber, means for securing the casing to the apparatus, a thermally actuated disk arranged within the chamber in heat transfer relation with the apparatus, a switch actuated in a snap-acting manner by the disk to open and closed positions in response to predetermined low and high temperatures of the apparatus, respectively, a spring disposed between the disk and said flexible wall for determining the temperatures at which the disk actuates the switch, said switch and spring being disposed within the hermetically sealed chamber, means disposed exteriorly of the casing and engaging the flexible wall for adjusting the bias of the spring, said adjusting means including a rotatable element, the axis of which is arranged at an angle to the axis of the disk and a handle carried by said rotatable element for adjusting the same at will.

7. The combination as claimed in claim 6 including means for adjusting the bias of the spring independently of said rotating element.

8. In a control mechanism for electrically-controlled apparatus, the combination of a cup-shaped casing having one end thereof secured in heat transfer relation with the apparatus, a wall closing the other end of the casing and secured thereto to provide a hermetically-sealed chamber, said wall having a flexible portion, a thermal-responsive element secured to the casing and disposed within said chamber at the end thereof remote from said wall, a switch disposed within the chamber and actuated by said element for controlling said apparatus and adjustable means cooperating with said flexible wall portion for varying the temperatures at which the thermal element actuates the switch.

9. In a control mechanism for electrically-controlled apparatus, the combination of a substantially cylindrical casing having an end wall secured in heat transfer relation with the apparatus, a wall having a flexible portion and secured by the fusion of metal to the end of the casing remote from said first end wall, whereby a hermetically-sealed chamber is defined within the casing, a snap-acting thermal-responsive disk secured to the casing adjacent the first-mentioned end wall and disposed within said chamber, a switch for controlling the apparatus and actuated by said disk, means for providing a bias on said disk for determining the temperatures to which it responds to operate the switch, said biasing means bearing against the inside of said flexible wall portion and means bearing upon the outside of the flexible wall portion for adjusting the bias of the biasing means whereby said temperatures may be varied at will.

10. The combination as claimed in claim 9 hav-

- ing a second means for adjusting the bias of the biasing means independently of said first adjusting means.
5. 11. In a control mechanism, the combination of a casing structure having a flexible wall and defining a substantially enclosed chamber, a switch disposed within the chamber and having open and closed positions, a thermal-responsive element for actuating the switch, resilient means 10 cooperating with the flexible wall for applying a bias to the thermal-responsive element and ad-

justable means cooperating with the flexible wall for varying the bias of the resilient means on the thermal-responsive element, whereby the temperatures at which the thermal-responsive element operates the switch are varied, said adjustable means being adjustable to a position where the switch is maintained in one of its positions regardless of the temperature of the thermal-responsive element.
